UNITED STATES PATENT OFFICE.

HALSEY J. MITCHELL, OF SCHENECTADY, NEW YORK.

COMBINATION SALT AND PEPPER SHAKER.

1,209,318.

Specification of Letters Patent.

Patented Dec. 19, 1916.

Application filed May 26, 1916. Serial No. 100,094.

To all whom it may concern:

Be it known that I, HALSEY J. MITCHELL, a citizen of the United States, residing at Schenectady, in the county of Schenectady, 5 State of New York, have invented a new and useful Combination Salt and Pepper Shaker; and I do hereby declare the following to be a full, clear, and exact description of the invention, such as will enable 10 others skilled in the art to which it appertains to make and use the same.

The present invention relates to a combination salt and pepper shaker, and has for its object to provide a device of this character which embodies novel features of construction whereby both the salt and pepper are contained in a single receptacle, although either may be shaken out to the exclusion of the other, as desired.

20 Further objects of the invention are to provide a device of this character which is comparatively simple and inexpensive in its construction, which can be easily manipulated, which confines the salt and pepper in 25 such a manner that they can not become mixed with each other, and which can be handled in the same manner as an ordinary salt shaker.

With these and other objects in view, the 30 invention consists in certain novel combinations and arrangements of the parts as will more fully appear as the description proceeds, the novel features thereof being pointed out in the appended claims.

35 For a full understanding of the invention, reference is to be had to the following description and accompanying drawing, in which:—

Figure 1 is a top plan view of a combination salt and pepper shaker constructed in 40 accordance with the invention. Fig. 2 is a side elevation thereof, one of the valve plates being shown in an open position. Fig. 3 is a transverse vertical sectional view through 45 the same.

Corresponding and like parts are referred to in the following description and indicated in all the views of the drawings by the same reference characters.

50 Referring to the drawings, which illustrate one possible embodiment of the invention, the reference character 1 designates a receptacle which is substantially cylindrical in shape, the upper end thereof being closed by a removable perforate cover 2. The interior of the receptacle 1 is subdivided by a

longitudinal partition 3 into two independent compartments 4 and 5 adapted to receive different condiments, such as salt and pepper. The cover 2 is preferably flanged so as 55 to telescope upon the upper end of the receptacle 1, a union 6 being shown as provided for locking the cover in position. This union 6 may have a swiveled connection with the flange of the cover 2, as indicated 65 at 7, and have a threaded engagement 8 with the receptacle, so that by tightening the union the cover can be drawn tightly into position. The inner face of the cover is provided with a transversely extending depression or seat 9 adapted to receive the upper edge of the partition 3, when the cover is locked in position, thereby preventing any possibility of the salt and pepper in the compartments 4 and 5 becoming mixed with 75 each other.

As previously explained, the cover 2 is perforated, one-half thereof closing the upper end of the compartment 4, while the other half thereof closes the upper end of the 80 compartment 5. The perforations of each half of the cover are normally closed by a valve plate 10, said valve plates being hingedly connected at their outer ends to diametrically opposite sides of the cover 2, as indicated at 11, the axis of each hinged joint being just sufficiently spaced from the edge of the cover to provide a seat for a spring arm, as will be hereinafter described. A finger lever 12 projects rearwardly from the hinged 85 end of each of the valve plates 10, an offset portion 12a being provided at the junction of the lever and the valve plate for the purpose of providing the necessary clearance space for the edge of the cover 2 when the finger lever is pressed downwardly to swing the valve plate upwardly into an open position. The end of each finger lever 12 is returned downwardly to provide a spring arm 13, the extremity of the said spring arm engaging the before mentioned seat between the axis of the valve plate and the extreme edge of the cover 2, so that the resiliency of the spring arm normally tends to hold the valve plate against the top of the cover 2, thereby closing all of the perforations on that side of the cover, so that the condiment within the corresponding compartment of the receptacle can not escape, even though the receptacle be inverted and shaken vigorously. If desired, the valve plates 10 may be provided with short studs 15 arranged to

enter the perforations of the cover 2 when the valve plate is in a closed position, thereby rendering it certain that neither the salt nor the pepper will escape or leak out when 5 the valve plate is closed.

Both of the valve plates 10 are normally held yieldingly in a closed position by the action of the spring arms 13, as previously described. When it is desired to use either 10 the salt or the pepper, the corresponding finger lever 12 is pressed downwardly to open the proper valve plate 10, whereupon the desired condiment can be shaken out in the usual manner. In the event it might be 15 desired to discharge both salt and pepper at the same time, the desired result could be accomplished by simultaneously swinging both of the finger levers 12 rearwardly toward the sides of the receptacle.

Having thus described the invention, what I claim as new and desire to secure by Letters Patent, is:—

1. A combined salt and pepper shaker, including a receptacle subdivided into two independent compartments, a perforate cover applied to the receptacle with substantially one-half thereof closing one of the compartments, while the other half thereof closes the opposite compartment, independent 25 valve plates hingedly connected to diametrically opposite sides of the cover at points slightly spaced from the periphery thereof, said valve plates normally closing the perforations in the respective halves of the cover, finger levers projecting rearwardly from the hinged 30 ends of the valve plates and offset outwardly at their junction with the valve plates to provide a clearance space for the edge of the cover when the finger levers are swung rearwardly to open the valve plates, the ends of the finger levers being returned to provide 35 spring arms which engage the cover between the edge thereof and the axes of the valve plates, the resiliency of the spring arms normally holding both of the valve plates in a closed position.

valve plates to provide a clearance space for the edge of the cover when the finger levers are swung rearwardly to open the valve 40 plates, and springs normally holding the valve plates in a closed position.

2. A combined salt and pepper shaker, including a receptacle subdivided into two independent compartments, a perforate cover 45 applied to the receptacle with substantially one-half thereof closing one of the compartments, while the other half thereof closes the other compartment, independent valve plates hingedly connected to diametrically 50 opposite sides of the cover at points slightly spaced from the periphery thereof, said valve plates normally closing the perforations in the respective halves of the cover, finger levers projecting rearwardly from the hinged 55 ends of the valve plates and offset outwardly at their junction with the valve plates to provide a clearance space for the edge of the cover when the finger levers are swung rearwardly to open the valve plates, the ends of the finger levers being returned to provide 60 spring arms which engage the cover between the edge thereof and the axes of the valve plates, the resiliency of the spring arms normally holding both of the valve plates in a 65 closed position.

In testimony whereof I have signed my name to this specification in the presence of two subscribing witnesses.

HALSEY J. MITCHELL.
